MICHAEL H. FLYNN, OF HARTFORD, CONNECTICUT, ASSIGNOR TO THE M. S. LITTLE MANUFACTURING COMPANY, OF HARTFORD, CONNECTICUT.

FLUSHING-VALVE.

1,368,208.

Specification of Letters Patent.

Patented Feb. 8, 1921.

Application filed December 11, 1919. Serial No. 344,089.

To all whom it may concern:

Be it known that I, MICHAEL H. FLYNN, a citizen of the United States, and a resident of Hartford, in the county of Hartford, 5 State of Connecticut, have invented certain new and useful Improvements in Flushing-Valves, of which the following is a specification.

The object of the present invention is to 10 provide an improved flushing valve which is simple in construction, and efficient and practically noiseless in operation; which is capable of ready adjustment, and wherein the length of flush is predetermined irrespec- 15 tive of the duration of time that the manipulated member is held in actuated position.

In the accompanying drawing the figure 20 is a vertical sectional view of a flushing valve constructed in accordance with the preferred embodiment of the present invention.

Referring to this drawing in detail, 10 is a valve casing having at one side an inlet opening 12 and at its bottom an outlet opening 13. Between the inlet and outlet openings is a cylindrical extension 14, the upper end of which serves as a seat for the main valve 15. The upper end of the valve casing is closed by a cap 16 having a port 17 which, together with a port 18 in the wall of the 25 casing, forms a bypass permitting communication between the pressure chamber 11 above the main valve and the outlet opening 13. The port 17 has a valve seat 19 located on the bottom of the cap 16 and 30 against which seats a control valve 21 carried by a reciprocating stem 22 extending through the cap 16. For the purpose of varying the length of flush, this valve 21 is adjustable on the stem, in the present instance it being 35 in the form of a castellated nut held in adjusted position by means of a cotter pin 23 extending through an elongated slot in the valve stem.

The main valve 15, consisting by pref- 40 erence of a single casting devoid of packing or washers, has a port 24 therethrough whereby the inlet pressure is communicated to the chamber 11 above the valve 15. This port 24 comprises, in part, a centrally lo- 45 cated bore 25 leading downwardly from the upper face of the valve 15.

On the lower end of the valve stem 22 50 is a pin 27 aligned with the bore 25 and of slightly less diameter than the same so that 55 when either of the valves 15 or 21 is open,

the pin will extend into this bore, and the latter is thereby restricted to limit the flow of fluid from the inlet opening to the chamber above the main valve. This pin has a two-fold function in that it keeps the bore 60 25 in a clean condition, and restricts the flow of fluid therethrough and thus aids in controlling the length of flush. To permit of adjustment of the pin 27, it is screwed into a threaded recess in the end of the stem 22 65 and locked in adjusted position by a nut 28. Preferably this pin is so adjusted that when the valves 15 and 21 are closed (as shown in the drawings) the lower end of the pin terminates just short of the bore 25, this being 70 of advantage in that the port 24 is then unrestricted so that the full force of pressure within the inlet opening 12 may be communicated to the chamber 11 to maintain the valves in closed positions.

It will be readily seen that when the valve 21 is adjusted on the stem 22 to change the length of flush, the pin 27 may also be adjusted so that the lower end of the same, when the valves 15 and 21 are in closed positions, will be in the relation to the port 25 just described.

For the purpose of limiting the length of flush, means is provided for preventing the control valve 21 from being held in open 85 position beyond a predetermined duration of time by holding the manipulating member in operative position.

The manipulating member is herein shown as being in the form of a push button 30 90 mounted for movement in the outer end of a cylindrical extension 31 on the cap 16 and normally urged outwardly thereof by a spring 32 resting on a bushing 33 fixed in the extension. Pivoted on the manipulat- 95 ing member is a pawl 34 having a notch 35 which receives the edge of a head 36 on the outer end of the stem 22. The lower end of the pawl 34, which is of increased width, extends into an undercut groove in the bush- 100 ing 33 and has similarly inclined spaced surfaces 37 and 38 adapted to respectively co-operate with inclined surfaces 39 and 40 on the overhanging wall and bottom wall respectively of the groove. It will be noted 105 that the opposed inclined surfaces 39 and 40 are spaced apart a greater distance than are the surfaces 37 and 38 of the pawl so that when the surfaces 38 and 40 come into engagement, the pawl will be swung away 110

from the head 36 and when the manipulating member moves outwardly of the extension 31 the engagement of the inclined surfaces 37 and 39 will cause the pawl to swing 5 into engagement with the head 36.

The operation of the flushing device is, briefly, as follows. With the parts shown in the position of the figure of the drawing, the fluid within the chamber 11 is under inlet 10 pressure and retains the main valve 15 and the control valve 21 in closed positions. Upon depression of the push button 30, the control valve, due to the engagement of the shoulder 41 of the pawl against the head 15 15 36 of the valve stem, will be moved into open position and communication between the chamber 11 and the outlet opening 13 is established through the bypass 17, 18 and this results in a reduction of pressure in the 20 chamber 11 so that the inlet pressure on the bottom of the main valve 15 moves the same away from its seat and direct communication is thereby established between the inlet opening 12 and the outlet opening 13. As 25 the manipulating member reaches the end of its operative stroke, the pawl 34, due to engagement of surfaces 38 and 40, will be swung in a direction to withdraw the shoulder 41 from the head 36 and thereafter the 30 control valve is free to automatically close, although the manipulating member may be further held in depressed position. After the valve stem is thus released from the pawl, the control valve, due to suction of 35 the fluid as it passes into the bypass, will be drawn into closed position, but if this force of suction is not strong enough to accomplish this result, the main valve will engage the valve stem 22 and positively move the same 40 to seat the control valve. After the control valve is seated, fluid from the inlet opening will flow through the port 24 in the main valve and, due to the pressure thus built up in the chamber 11, the main valve is forced 45 to its seat. After the push button is released, the spring 32 will move same outwardly, and the surface 37 of the pawl will engage the inclined surface 39 of the bushing so that the pawl will be thrown into the 50 operative position shown in the drawing. It will be readily understood that if a shorter length of flush is desired, the control valve 21 will be adjusted upwardly on the stem 22, to shorten the distance this valve is moved 55 away from its seat upon depression of the push button, and when a longer flush is desired, the control valve is adjusted downwardly on its stem 22.

While the form of mechanism herein 60 shown and described is admirably adapted to fulfil the objects primarily stated, it is to be understood that it is not intended to confine the invention to the one form of embodiment shown and described herein, as 65 it is susceptible of embodiment in various

forms, all coming within the scope of the claims which follow.

I claim as my invention:

1. In a flushing device, a casing having an outlet opening and an inlet opening, a main valve controlling said outlet opening, a pressure chamber behind said main valve, a port in the main valve permitting communication between said inlet opening and pressure chamber, a bypass between said pressure chamber and outlet opening, a valve stem, a control valve thereon controlling said bypass and opening toward said main valve, and a pin on said stem alined with the port of said main valve and terminating 75 adjacent to but short of said port when said valves are in closed position.

2. In a flushing device, a casing having an outlet opening and an inlet opening, a main valve controlling said outlet opening, a pressure chamber behind said valve, a port in said main valve permitting communication between the inlet opening and said chamber, a bypass between said chamber and outlet opening, a valve stem, a control valve 85 adjustable thereon controlling said bypass and opening toward said main valve, and a pin adjustably carried by said stem alined with said port of said main valve and terminating adjacent to but short of said port 90 when said valves are closed.

3. In a flushing device, a casing having an outlet and an inlet opening, a main valve controlling one of said openings, a pressure chamber behind said main valve, a control 100 valve for controlling the relief of pressure therein, a valve stem carrying said control valve, a manipulating member, a connection carried by said manipulating member and engaging said stem, and means for moving 105 said connection out of engagement with said stem when the manipulating member approaches the end of its operative stroke.

4. In a flushing device, a casing having an inlet and an outlet opening, a main valve 110 controlling one of said openings, a pressure chamber behind the main valve, a control valve controlling the relief of pressure therein, a valve stem carrying said control valve, a manipulating member, a connection carried by said manipulating member and engaging said stem, means for moving 115 said connection out of engagement with said stem when the manipulating member approaches the end of its operative stroke, 120 and means for moving said connection into engagement with said stem when the manipulating member approaches the end of its inoperative stroke.

5. In a flushing valve, a casing having an 125 inlet and an outlet opening, a main valve controlling one of said openings, a pressure chamber behind said main valve, a control valve controlling the relief of pressure therein, a valve stem carrying said control 130

- valve, a manipulating member, a connection carried by said manipulating member and engaging said stem, means for moving said connection out of engagement with said stem when the manipulating member approaches the end of its operative stroke, means for moving said connection into engagement with said stem when the manipulating member approaches the end of its inoperative stroke, and means for relatively adjusting said stem and connection to vary the throw of the control valve upon actuation of the manipulating member and thereby change the length of flush.
- 10 5. In a flushing device, a casing having an inlet opening and an outlet opening, a main valve controlling one of said openings, a pressure chamber behind the main valve, a control valve for relieving pressure therein, a stem carrying said control valve, a manipulating member, a pawl pivotally carried thereby and engaging said stem, opposed similarly inclined cam surfaces on the casing, and a pair of inclined surfaces on said pawl spaced at a less distance than are the surfaces on said casing and adapted to engage therewith to move the pawl out of engagement with the stem when the manipulating member approaches the end of its operative stroke, and into engagement when the manipulating member approaches the end of its inoperative stroke.
- 15 6. In a flushing device, a casing having an inlet opening and an outlet opening, a main valve controlling one of said openings, a

MICHAEL H. FLYNN.
